ATTYS.

UNITED STATES PATENT OFFICE.

JAMES CHRISTY, OF AKRON, OHIO.

DESIGN FOR A VEHICLE-TIRE.

46,428.

Specification for Design.

Patented Sept. 22, 1914.

Application filed July 21, 1913. Serial No. 780,406. Term of patent 14 years.

To all whom it may concern:

Be it known that I, JAMES CHRISTY, a citizen of the United States, residing at Akron, county of Summit, and State of Ohio, have invented a new, original, and ornamental Design for a Vehicle-Tire, of which the following is a specification, reference being had to the accompanying drawing, forming part thereof.

Figure 1 is a perspective view of the tire

on a reduced scale showing my new design, and Fig. 2 is an elevation of a portion thereof approximately full size.

I claim:

The ornamental design for a vehicle tire, as shown.

JAMES CHRISTY.
